Atty's.

UNITED STATES PATENT OFFICE.

ERNESTO MAGGIORA, OF TURIN, ITALY.

EXPLOSION-ENGINE CYLINDER.

Application filed June 1, 1926, Serial No. 113,017, and in Italy June 15, 1925.

The present invention relates to combustion engines and more particularly to cylinders of engines of the kind in which each cylinder is provided with an opening leading from outside to the combustion space for the purpose of removing soot and scales therefrom and has a removable plug intended to close said opening.

The present invention has for its object 10 the provision for water circulation through said plug closing the cylinder cleaning opening and according to the present invention said plug is made hollow and the space within it is put in communication with the 15 water jacket of the cylinder for the purpose of cooling it; according to a further feature of this invention said water jacket has ports in its outer portion and the said plug has a flange abutting against said 20 water jacket portion and provided with ports registering with the water jacket ports.

A further feature of this invention is the provision of means in the water jacket for assisting the water circulation through said 25 plug.

On the annexed drawing is shown by way of example an embodiment of the present invention and

Figure 1 is a side view of a block of cylinders of an explosion engine with a portion in sectional view and with the feature of the present invention embodied therein;

Figure 2 is a transverse section on line II-II of Fig. 1;

Figure 3 is a sectional view of a separate plug on enlarged scale;

Figure 4 is a view of the plug as viewed in the direction of the arrow IV in Fig. 3;

Figure 5 is a sectional view of said plug 40 on the line V-V of Fig. 3.

As shown in Figures 1 and 2, on one side of the cylinder block 1, in the wall of each cylinder in register with the explosion chamber of the same (shown by 14), is provided 45 a port 2 having any desired shape and leading to engine cylinder explosion chamber, said port being encircled by walls separating it from the water jacket 5.

Said port is closed by means of a plug 50 referred to in its whole by 3 and herein-after particularly described, which is fastened in position by means of screws 4 passing through a portion of said plug and engaging screw threaded holes 7 of the water jacket wall.

Said plug comprises a hollow body 8

adapted to project through the water jacket space and to flush with the internal wall of the cylinder chamber 14, and an enlarged hollow section which provides a head 6 extending outwardly with respect to plug body 3; the hollow of said head is in communication with the hollow of body 3.

The wall of head 6 has enlarged portions 15 passed through by holes 8 intended to receive bolts 4 fastening the plug in position on the cylinder, and the front portion of the head provides a wall 16 adapted to abut on the cooperating wall 17 of the water jacket wall.

In registering portions of said water jacket and plug head, walls are provided ports 10-9 putting the hollow of said plug in communication with the space inside the water jacket; more particularly said ports 70 9-10 are provided along the entire periphery of head or flange 6 of the plug and cooperating seat of the water jacket wall, a portion of them being thus located under the plug body and another portion of them 80 being above said plug body.

When the plug is in position on the cylinder as shown by Figure 2, the cooling water flowing through water jacket 5 enters the hollow of head 6 through the lower ports 85 10 and 9 and flows through the plug hollow, it being then discharged through top ports 9 and 10 into the top portion of the water jacket 5.

In order to improve the water circulation 90 through the plug, in the top space of the water jacket above said seat 2 and plug 3 is provided an upwardly projecting baffle or partition 11 connected with transverse partitions 12 extending from the adjacent wall 95 of the water jacket to said partition 11, said partitions 11-12 providing inside the water jacket 5 a pocket in which open the top ports 9-10 and which in turn opens through orifice 13 into the top portion of the water 100 jacket 5.

Thus the water which is strongly heated in plug 3 owing to its slow circulation through the same, is discharged into the top portion of the water jacket where the circulating water is very hot, and is conveyed directly to radiator (not shown); thus a uniform and correct circulation is promoted through plug 3.

Of course this invention is not restricted 110 to the embodiment described and illustrated, it being only confined by appended claims.

What I claim as my invention and desire to secure by United States Letters Patent is:—

1. A water jacketed cylinder for explosion engines having an opening leading to cylinder explosion chamber, a hollow plug closing said opening and means for producing a water circulation through said hollow plug.
2. A water jacketed cylinder for explosion engines having an opening leading to cylinder explosion chamber, a hollow plug closing said opening and means for producing a water circulation from and to said water jacket through said hollow plug.
3. A water jacketed cylinder for explosion engines having an opening leading to cylinder explosion chamber, a hollow plug closing said opening, said water jacket and plug having abutting surfaces and registering ports in said surfaces for producing a water circulation through said hollow plug.
4. A water jacketed cylinder for explosion engines having an opening leading to the cylinder explosion chamber, a hollow plug filling said opening, an enlarged hollow head on said plug, said water jacket and plug head having abutting surfaces and registering ports in said surfaces for providing a water circulation through said hollow plug.
5. A water jacketed cylinder for explosion engines having an opening leading to cylinder explosion chamber, a hollow plug filling said opening, an enlarged hollow head on said plug, said water jacket and plug head having abutting surfaces and registering ports in said surfaces for providing a water circulation through said hollow plug, and cooperating means on said plug head and water jacket for fastening said plug in position.
6. A water jacketed cylinder for explosion engines having an opening leading to cylinder explosion chamber, a hollow plug filling said opening, an enlarged hollow head on said plug, said water jacket and plug head having abutting surfaces and registering ports in said surfaces for providing a water circulation through said hollow plug, and cooperating bosses in said head and bolts passing through holes in the same and engaging said water jacket to fasten said plug in position.
7. A water jacketed cylinder for explosion engines having an opening leading to cylinder explosion chamber, a hollow plug closing said opening, means for producing a water circulation through said hollow plug from and to said water jacket, and means in said water jacket for promoting said water circulation through said plug.
8. A water jacketed cylinder for explosion engines having an opening leading to cylinder explosion chamber, a hollow plug closing said opening, said water jacket and plug having abutting surfaces and ports for providing for a water circulation through said
9. A water jacketed cylinder for explosion engines having an opening leading to the cylinder explosion chamber, a hollow plug filling said opening, an enlarged hollow head on said plug, said water jacket and plug head having abutting surfaces and registering ports in said surfaces for providing a water circulation through said hollow plug, and means in said water jacket for promoting a water circulation through said plug.
10. A water jacketed cylinder for explosion engines having an opening leading to cylinder explosion chamber, a hollow plug closing said opening and means for providing for a water circulation from and to said water jacket through said hollow plug, a partition providing a pocket in said water jacket, said pocket discharging in the top portion of said water jacket and receiving water issuing from said plug.
11. A water jacketed cylinder for explosion engines having an opening leading to cylinder explosion chamber, a hollow plug closing said opening, said water jacket and plug having abutting surfaces and registering ports in said surfaces for producing a water circulation through said hollow plug, a partition providing a pocket in said water jacket, a number of said ports opening in said pocket and said pocket having an outlet opening in the top portion of said water jacket.
12. A water jacketed cylinder for explosion engines having an opening leading to cylinder explosion chamber, a hollow plug closing said opening, said water jacket and plug having abutting surfaces and registering ports in said surfaces above and under said opening for producing a water circulation through said hollow plug, a partition providing a pocket in said water jacket, the ones of said ports above said opening communicating with said pocket, and said pocket having an outlet opening in the top portion of said water jacket.
13. A water jacketed cylinder for explosion engines having an opening leading to cylinder explosion chamber, a hollow plug filling said opening, an enlarged hollow head on said plug, said water jacket and plug head having abutting surfaces and registering ports in said surfaces for providing for a water circulation through said plug, a partition in said water jacket providing a pocket in the same in which open a number of said ports, and said pocket having an outlet opening in the top portion of said water jacket.

In testimony whereof, I affix my signature.

ERNESTO MAGGIORA.
